UNITED STATES PATENT OFFICE.

WILLIAM HUGHES, OF BEAVER MEADOWS, PENNSYLVANIA.

AIR-SANDER.

No. 892,426.

Specification of Letters Patent.

Patented July 7, 1908.

Application filed October 29, 1907. Serial No. 399,689.

To all whom it may concern:

Be it known that I, WILLIAM HUGHES, a citizen of the United States, residing in Beaver Meadows, in the county of Carbon and 5 State of Pennsylvania, have invented a new and useful Improvement in Air-Sanders, of which the following is a specification.

This invention relates to a sanding device in which the discharge spouts are controlled 10 by a valve operated by compressed air and in which the sand will be discharged at the will of the engineer through either of two discharge pipes thereby avoiding waste of sand, which waste occurs in sanding devices 15 where the sand is fed through both pipes when the feed of sand is required through one of the pipes only.

The invention consists of the novel features of construction hereinafter described, 20 pointed out in the claims and shown in the accompanying drawings in which—

Figure 1 is an outlined view illustrating the location of the device upon a locomotive. Fig. 2 is a side elevation of my device. Fig. 25 3 is a front elevation. Fig. 4 is a vertical, longitudinal section. Fig. 5 is a horizontal section taken through a valve and valve casting.

In these drawings 1 represents a sand box 30 and 2 a sand pipe conveying sand from the box 1 to my device which consists of a casting 3 in the upper portion of which is fitted a rotatable valve 4 provided with a handle 5. By means of this valve flow of sand can be 35 cut off between the sand box 1 and the lower portion of the casing 3, the front of said casing being closed by a removable front plate 3^a. By removing this plate and turning the valve 4 sand can be cut off while cleaning 40 damp sand from the lower portion of the casing. From this lower portion lead oppositely extending discharge nozzles 6 and 6^a. Within the lower portion is a valve casing 45 which may be of brass or other suitable metal and which at one end carries a cylindrical sliding valve 8 provided with a piston 9 against which compressed air may work. To admit air to either side of the piston 9 50 passages 10 and 10^a are formed in the casing 7 which is provided also with side openings 11 which communicate with said passages.

The outer ends of the passages 10 and 10^a being closed by reason of the casing 7 bearing against the rear wall of the casting 3. With 55 this construction the passages 10 and 10^a can

be very easily cleaned out by removing the valve casing 7 from the casting. The piston valve 8 works in a cylindrical chamber 12 formed in the valve casing and into which the passages 10 and 10^a lead. At each end 60 of the valve is an angle bore 13 which opens through the adjacent end of the valve and also through the side, one of said bores being in communication with the chamber 12 while the other is closed by the end of head 65 portion of the chamber 12, as indicated by the dotted lines in Fig. 4. Discharge pipes 14 and 14^a lead respectively from the nozzles 6 and 6^a and air devices 15 and 15^a lead respectively to the passages 10 and 10^a. 70

The operation of the device is as follows:— When the device is in use sand flows through the pipe 2 into the casing 3 and downwardly into the lower portion of the casing in which portion is arranged the valve casing 7. The 75 sand is then acted upon by an air jet from either end of the valve 8, said jet issuing from one of the bores 13. When it is desired to discharge sand through the pipe 14 and to prevent discharge of sand through pipe 14^a 80 air is admitted through the pipe 15 and through the bore of passage 10 into the chamber 12. This forces the valve 8 toward the nozzle 6^a in which it stays thus preventing passage of sand to the pipe 14^a. This also 85 opens the passage of the pipe 14 through the nozzle 6 and the discharge of sand through said nozzle and through the pipe 14 is aided by the exhaust of air through the bore 13 one end of which is in alinement with the 90 nozzle 6 while the other end communicates with the chamber 12. Should it be desired to discharge air through pipe 14^a, as when running backward, air is admitted through pipe 15^a and the operation is reversed. 95

Having thus fully described my invention, what I claim as new and useful and desire to secure by Letters Patent is:—

1. In a device of the kind described, a casting having oppositely arranged discharge nozzles, a piston valve adapted to alternately seat itself in said nozzles and close the same, and means for admitting compressed air to said valve and upon either side of the piston. 100

2. In a device of the kind described a casting having oppositely arranged discharge openings, a valve casing, a sliding valve adapted to close over the said openings, a piston on said valve and within the valve 110

- casing, and means for admitting compressed air into the valve casing and upon either side of said piston.
3. In a sanding device a casting interposed between two discharge pipes and the feed pipe, a piston valve arranged in said casting and adapted to automatically open and close said discharge pipes, and means for reciprocating said valve.
4. In a device of the kind described comprising a casting having a cut off valve at its upper portion and a removable front plate in its lower portion, a valve casing placed in said lower portion said valve casing having a cylindrical chamber formed therein and having air passages communicating with said chamber, a sliding valve working in said chamber and projecting over the lower portion of the casing having discharge pipes in alinement with said valve, one of said openings being closed by the valve when the other opening is cleared, a piston upon the
- valve between the air passages, and means for admitting air to either of said air passages, the said piston valve having exhaust bores at each end.
5. The combination with a sanding device comprising a casting having discharge openings at its ends, of a valve casing arranged between said openings, a suitable slideable valve working in said casing and adapted to alternately close said openings, said valve having bores in its end portions each of said bores opening through a side and an end of the valve, a piston upon the valve and means for admitting a fluid under pressure upon either side of the piston, said fluid exhausting through one of said bores as and for the purpose set forth.

WILLIAM HUGHES.
